Inventor

Percy M. Smith.

UNITED STATES PATENT OFFICE.

PERCY M. SMITH, OF BUSHNELL, ILLINOIS.

ADJUSTABLE COLLAR BUTTON.

Application filed August 4, 1923. Serial No. 655,614.

To all whom it may concern:

Be it known that I, PERCY M. SMITH, a citizen of the United States, residing at Bushnell, in the county of McDonough and 5 State of Illinois, have invented certain new and useful Improvements in Adjustable Collar Buttons, of which the following is a specification.

This invention relates to adjustable collar buttons and more particularly to an improved button which may be attached to the neckband of a shirt or waist so that the neckband may be adjusted to properly fit the neck of the wearer.

15 The primary object of the invention is to provide a collar button of this character which may be adjustably connected to one end of the neckband and which will be adapted to be buttoned to the opposite end 20 of the neckband thus permitting the wearer to adjust the button at any point on the neckband so that the latter may be shortened or lengthened to properly fit the neck.

Other objects of the invention will appear 25 upon consideration of the following detailed description and accompanying drawing in which:

Figure 1 is a front elevation of the device showing it applied to a neckband,

30 Figure 2 is a plan view of same,

Figure 3 is a back view, and

Figure 4 is a cross section on the line 4—4 of Figure 3.

Referring to the drawing by numerals, 35 the plate 1 is relatively narrow and substantially rectangular in form and is longitudinally curved to conform to the curvature of the neckband of a shirt or waist. Projecting laterally from the plate 1 is the button 40 which includes the button shank 2 and the head 3 of conventional form. At the back of the plate, a pin 4 is hingedly mounted and this pin comprises the shank 5 provided at one end with a pintle 6 receivable in the 45 sockets 7 so that the pin may freely swing. The opposite end of the pin is pointed and is receivable in a notch 8 when the pin is applied and in position.

When the neckband is too long to properly 50 fit the neck of the wearer, the pin will be applied to one end of the neckband at a point which will cause the button to engage the button-hole on the opposite end of the band so that the neck band will snugly fit

in a comfortable manner. The button of 55 course will be disposed in a position to readily engage the button-hole in one end of the neck band and may be utilized in the usual manner to secure a collar on the neckband. When the neckband is too short, the 60 pin may be moved to the extreme end of one end of the neck band and the opposite end engaged by the button. In this manner an adjustment may be made so that the wearer may be assured of a comfortable fit 65 of the neckband around his neck.

Minor changes may be made in the details of construction without departing from the spirit of the invention or the scope of the claims hereunto appended. 70

What I claim is:

1. An adjustable collar button for the neckband of a shirt comprising a curved plate conforming to the curvature of the neckband, a button including a shank extending laterally from the plate and having a head on its free end, a pin comprising a pin shank having a pintle rigidly secured to one end, means on said plate to pivotally receive the ends of said pintle, the 75 opposite end of the pin being pointed, a notch in the said plate to receive the pointed end of the pin, the said plate being elongated and substantially rectangular whereby longitudinal adjustment of the plate on the 80 neckband may be made by the pin to vary 85 the position of the said button.

2. An adjustable collar button comprising, in combination with a neckband of a shirt or other garment, an elongated rectangular plate of a width less than the width of the neckband and longitudinally curved to conform to the curvature of the neckband, a button comprising a shank laterally projecting from the said plate and equipped 90 with a head at its free end, a fastening pin comprising a pin shank, a pintle rigidly carried by one end of the shank, sockets carried by the plate to receive the ends of said pintle whereby the pin may be movably 95 mounted, and means to receive the opposite pointed end of the pin. 100

In testimony whereof, I have affixed my signature in the presence of two witnesses.

PERCY M. SMITH
